(57) **CLAIM**

The ornamental design for a display screen with graphical user interface, as shown and described.

DESCRIPTION

FIG. 1 is a front view of a display screen with graphical user interface showing the new design; and, FIG. 2 is an enlarged view of the claimed region of the display screen with graphical user interface shown in FIG. 1. The broken line showing of the remainder of the user interface and the display screen is for environmental purposes only and forms no part of the claimed design.

1 Claim, 2 Drawing Sheets

FIG. 1

FIG. 2
